WARBLING WHISTLE

John H. Bacon, Wellesley, Mass.; Robert C. Bacon, administrator of said John H. Bacon, deceased

Application February 10, 1956, Serial No. 564,317

14 Claims. (Cl. 46—118)

The present invention relates to an improved construction for a warbling whistle. The present invention provides a design for a warbling whistle which is particularly adapted to be manufactured of plastic material and which can be animated.

One of the most important considerations in the manufacture and sale of toy whistles, is the cost of manufacture, for the toy whistle trade is a highly competitive market with the result that sales success is in a large measure dependent upon manufacturing costs. Accordingly, it is an object of the present invention to provide a whistle which may be manufactured with a minimum labor and material cost. This is accomplished in a large part by providing a whistle, manufactured entirely of plastic, with the plastic component parts being readily assembled. Included among the plastic members which are used in the structure of the present whistle, is a plastic stem adapted to provide a warbling sound to the whistle. This particular device enables a whistle to be constructed without the requirement of expensive spring steel members ordinarily used in similar types of whistles.

It is also an object of the present invention, to provide a warbling whistle construction which is of rugged construction and which will operate with a greater degree of certainty than those heretofore known. In this connection it should be noted that the warbling whistles of the prior art normally utilized a leaf spring structure which dips into the air stream effectively deflecting it and thus creating a warbling sound. Such whistle is shown in my prior Patent No. 2,697,298, patented December 21, 1954.

These whistles however will not operate properly if the leaf spring is bent or otherwise deformed, as often accidentally occurs. These problems presented by the use of such metal leaf spring both in the manufacture and sale, have been a considerable problem. In the present invention, however, a rigid deflecting member preferably manufactured of a plastic material, is utilized. This particular deflecting member, being rigid, does not present the same problems as those presented by utilization of a flexible leaf spring. Thus by the use of this rigid member which is pivotally supported, a more certain operation and ruggedness of construction may be obtained.

Further consideration in the present invention is the provision of a whistle structure which is adapted to be modified into a variety of attractive designs of commercial desirability.

In the present invention, these features are obtained by providing a whistle structure in which animation is readily obtained in part through the movement of the warbling stem, and in part through the movement of associated members. The present invention also provides a structure in which a variable sound may be selectively obtained independently of or simultaneously with an animation of the whistle.

These and other objects and advantages of the present invention will be more readily understood when considered in connection with the accompanying drawings, in which:

2

Figure 1 is a top plan view of the invention with the stem in an operative position.

Figure 2 is a cross sectional side view of the invention taken substantially along the line 2—2 of Figure 1.

5 Figure 3 is a cross sectional side elevation of a modification of the invention with the stem in an operative position.

Figure 4 is a cross sectional side view of another modification of the invention with the stem in an operative position.

10 Figure 5 is a cross sectional side elevation of another modification of the invention with the stem in an operative position.

Figure 6 is a cross sectional side view of another modification of the invention.

Figure 7 is a front elevation of a detail of the structure shown in Figure 6.

15 Figure 8 is a cross sectional plan view taken substantially along the line 8—8 of Figure 6, and,

20 Figure 9 is a cross sectional side elevation of another modification of the invention.

Referring specifically to the drawing of Figure 1 and Figure 2, there is disclosed a whistle structure made preferably of a plastic material such as polystyrene, in which 25 there is provided a casing 1, formed of two halves, 2 and 3, joined together longitudinally along the line 4 by suitable means such as cement. If desired, these two halves, 2 and 3, may interfit at their edges by a tongue and groove joint, or may if desired, have an abutting edge properly cemented together. Each of these halves 2 and 3 are provided with complementary interior structures such as is shown in cross section in Figure 2. Thus within the casing 1, there is provided an air inlet passage 5 extending from the mouth end 6 of the whistle to the constricted passage 7. This constricted passage 7, is formed between the roof 8 and the constricting wall 9. This constricted passage 7 directs a flow of air towards the knife edge 10, which is formed as a portion of the roof section 8. An opening 11 is provided between the end of the constricted passage 7 and the knife edge 10. The end 13 of a deflecting stem, generally designated as 12, projects through the opening 11. The stem 12 is formed of plastic material such as polystyrene, and consists preferably of an elongated stem section bent at one end 13, at an angle 30 substantially normal to the main portion 14 of the stem. The other end of the stem forms a ball socket 16 and consists essentially of two parallel arms 17 and 18 spaced apart from one another with openings 19 formed in the face of either arm. These arms have some degree of 35 resiliency which permits them to be forced about the ball 20 formed at the top of projecting stem 21. This stem 21 is in turn formed as a portion of the base 22, cemented or otherwise suitably secured to the roof 8. The ball 20 and socket 16 permit a free vertical pivoting of the stem 12 in such a manner that the end 13 may be moved readily up and down into the opening 11 and in such a manner that the end 13 will deflect the air passing through the constricted opening 7 from the knife edge 10, thus cutting off the whistle sound. It is to be noted that the stem 12 is 40 provided with its pivoted end closer to the mouth piece 6. It is to be noted that a section of the stem 12 forms a covering-like section which extends towards the mouth end above the constricted opening 7.

In Figure 3 there is shown a modification of the present invention, in which the casing 30 is formed in a similar manner as described in connection with the structure shown in Figure 1. The inside of this casing 30, has a wall section 31, forming together with one side of the casing, an air passage 32, which extends from the mouth piece 33 to a constricted mouth opening 34. This constricted mouth opening 34, is formed by the end of the wall 31 and the projecting wall 35. Air passing through

this constricted opening 34, is directed on to the knife edge 36 formed at the end of the wall 37, which may if desired be formed integrally with a top wall 38. In a separate compartment 39 of this whistle there is provided the warbling stem 40. This warbling stem 40 has an elongated center section 41 terminating at one end in a loop section 42, which is fitted over a transversely extending pin 43 formed integrally with the side walls of the casing. This warbling stem 40 freely pivots in a limited arc about this pin 43. At the other end of this warbling stem 41, there is provided a downwardly extending lip member 44, which projects through the opening 45 between the air deflecting knife edge 36 and the constricted opening 34. This deflecting lip 44 is adapted to be pivoted down into and out of this opening 45. In this modification, there is preferably provided a stem 47 which is integral with and extends upwardly from the lip end of the warbling stem. This stem 47 has supported at its upper end a figurine such as a bird figure 48. This stem 47 projects through an opening slot 49 in the top 38 of the whistle casing. If desired a cage like member 50 may be formed about the warbling bird figure 48 to simulate a bird in a cage setting. In the operation of this modification when air is blown through the mouth opening 33, the air will pass through the constricted opening 34. The air thus passing through the constricted opening 34, will force itself up against the downwardly extending lip 44, which substantially covers this constricted opening 34. When thus being acted upon by the force of air, the warbling stem will pivot upwardly simultaneously permitting air to impinge on the knife causing a whistling sound and also causing an apparent animation to the figurine 48. This warbling stem 40 will fall by its own weight back into the opening 45, thus causing an interruption and consequent warbling sound to emanate from the whistle. In this construction as well as in the others described, it is to be noted that the lip member at the end of the warbling stem, must be of sufficient size to satisfactorily impede the flow of air against the knife edge. The warbling stem, however, should not be so heavy as to prevent the air being forced into the constricted opening from lifting, in a pivoting fashion, this warbling stem from between the constricted passage and the knife edge. Nor should the warbling stem be so light as to always remain in a raised position outside of the air stream between the constricted opening and the knife edge. Thus the warbling stem must have just enough weight to fall back into the air stream once it has been pivoted upwardly out of the air stream.

In Figure 4 there is shown a still further modification of the invention in which the casing 60 is made in a fashion similar to that described previously in connection with the other modifications. In this structure there is provided an air passage 61 which conducts air from the mouthpiece 62 to the constricted air passage 63 formed between the roof 64 and the wall 65. This constricted air passage 63, directs air across the opening 66 in the roof 64 against the knife edge 67 formed transversely across the roof 64. In this modification, the warbling stem 68 is supported in the structure 69 which is formed in a suitable ornamental fashion, such for example as a bird figure. This supporting bird structure 69 is formed of two half sections with the half sections each integrally connected with the casing 60 at 70. The warbling stem 68 is supported within this bird structure 69 on a transversely extending pin 71 formed integrally with the side of the bird figure. This warbling stem 68 which is freely pivotable about the pin 71 at one end, has a downwardly extending lip section 72 formed at its other end. This lip section 72 is preferably formed to simulate the tongue of the bird and projects outwardly from the bird structure 69 through that portion of it which forms the mouth of the bird. The extreme end of this lip section 72 projects into the opening 66 and forms a deflecting tip 73.

If desired an upwardly extending section may be provided on the warbling stem with this section 75 having an eye disc 76 formed at its end. This eye disc is designed to align with an opening 77 in the wall of the bird, shaped as an eye opening. This structure operates similarly to the one previously described with the warbling stem 68 pivoting up and down into the opening 66 to provide a warbling whistle sound. Simultaneous animation is obtained in both the tongue and eye of the bird figure.

In Figure 5 there is shown a modification of the present invention having a casing 80, constricted opening 81, mouth opening 82 and air deflecting knife edge 83 formed in a manner as previously described. In this structure the warbling stem 84 is pivoted at a loop end 85 to the transversely extending pin 86 which is formed integrally with the side wall of the casing 80, in the upper compartment section 87. This warbling stem 84 has a downwardly extending lip 88 adapted to interrupt the flow of air into the opening 89. An upwardly extending section 90 at the lip end of the warbling stem, projects into the mouth of the bird figure 91 formed above the casing 80. This projecting section 90 should be so arranged relative to the mouth of the bird figure 91 as to simulate movement of the tongue upon up and down movement of the warbling stem. If desired an eye disc 92 may be positioned at the end of this section 90 to move across a corresponding eye opening in the bird figure 91. The bird figure 91 is formed of a shell of plastic material, pivotally supported above the casing 80. The support may comprise a projecting boss 93 having an opening through which pins 94 formed integrally with the side walls of the bird member 91 may pivotally project. This projecting boss or knob 93 passes through an opening 95 at the bottom of the bird figure.

Other equivalent structures for supporting this bird form may of course be utilized.

At the end of the bird form there is a projecting portion 96 which passes downwardly through an opening 97 in the roof of the casing. This projecting section 96 is adapted to engage the irregularly arranged surface 98 of the longitudinally extending operating rod 99. This operating rod 99 projects through the end 100 of the casing and has supported at its other end a piston member 101. The operating rod and piston are adapted to be moved longitudinally within the resonant chamber section 102, providing a resonant chamber of variable size. In the operation of this modification, a simultaneous movement of the bird tongue, eye and body may be obtained together with a selected warbling variation determined by the configuration of the surface 98. This warbling variation is accompanied by a change in the notes being played.

In Figure 6 there is illustrated a modification having a casing 110 forming by means of the inner wall section 111, air conducting chamber 112 which extends from the mouth opening 113 to the constricted air opening 114. This constricted air opening 114 extends downwardly and is directed towards the air deflecting knife edge 115 formed integrally with the bottom wall of the casing 110. Pivotally supported from a supporting structure 116, in this case formed in the shape of a bird cage, is the warbling stem 117. This warbling stem 117 also shown in Figure 7, has a pair of opposite legs 118 and 119, arranged parallel with the end discs 120 and 121 cooperating to form a socket. These members 120 and 121 have some resiliency and may be forced apart somewhat to permit the insertion of the ball 122, which in turn is supported on the stem 123. This stem 123 is secured to the top 124 of the supporting structure 116. This ball and socket arrangement, permits a free and easy pivotal movement of the warbling stem 117 in a forward and backward direction. The lower end of this warbling stem is provided with a bird figure 125 formed on the cross piece 126. A downwardly extending end

section 127 of the warbling stem, terminates in an inwardly turned lip 128, which is adapted to swing between the constricted opening 114 and the knife edge 115. The pivotal movement of the warbling stem is directed in the back and forth motion by the shape of the slot formed in the roof of the casing 110 and through which the lower section of the warbling stem projects. This modification provides a whistle structure in which the warbling sound is accompanied by a back and forth motion of the bird figure within the cage.

In Figure 9 there is shown a further modification of the invention in which the air constricting passage 140, knife edge 141, air conducting passage 142 and mouth opening 143 are similar to those described in connection with Figure 6. In this modification, the warbling stem 144 is supported in a central location by a pin 145 extending from and integral with the side wall of the casing 146. This pin 145 projects through a boss 147 formed on the warbling stem 144. The upper end of this warbling stem 144, has a bird like figure 148 positioned within the cage member 149 formed on the casing. The warbling stem projects into this cage 149 through a slot 150 which acts to guide the warbling stem in a back and forth motion, similar to that as described in connection with the modification of Figure 6. The lower end of this warbling stem is inwardly extending and forms the lip 151 which projects between the air constricting opening 140 and the knife edge 141. This modification operates in a manner similar to those previously described in which an oscillating motion of the figure is obtained by the force of the air passing out of the constricted mouth opening 140. An intermittent whistle sound is produced by the air as it is permitted to impinge upon the knife edge 141.

Having now described my invention, I claim:

1. A whistle having an air conduit terminating in a constricted air opening, an air deflecting edge aligned with said opening, a rigid stem having a lip section, and means pivotally supporting said stem to permit angular movement of said stem only about a fixed pivotal axis generally parallel to said edge with the lip section adapted to move downwardly to and upwardly from a position between said edge and opening, respectively under the force of gravity and under upward pressure of air against said lip section whereby said lip section will intermittently interrupt the flow of air between said edge and opening.

2. A whistle having an air conduit terminating in a constricted air opening, an air deflecting edge aligned with said opening, an elongated rigid stem having one end angularly turned to form a lip section, and means in part formed by the other end of said stem for pivotally supporting said stem to permit angular movement of said stem only about a fixed pivotal axis generally parallel to said edge with the lip section adapted to move downwardly to and upwardly from a position between said edge and opening, respectively under the force of gravity and under upward pressure of air against said lip section whereby said lip section will intermittently interrupt the flow of air between said edge and opening.

3. A whistle as set forth in claim 2 wherein said means pivotally supporting said stem comprise a ball and socket arrangement with said socket formed of a pair of facing surfaces with aligned recesses therein, said ball adapted to be resiliently received between said recesses.

4. In a whistle having a case forming an air conduit terminating in a constricted air opening and an air deflecting edge aligned with said opening, a rigid stem having a lip section formed at one end and a ring support at the other, means including a pin generally parallel to said edge freely projecting through said ring support for pivotally supporting said stem with the lip section adapted to move downwardly to and upwardly from a position between said edge and opening, respectively under the force of gravity and under upward pressure of

air against said lip section whereby said lip section will intermittently interrupt the flow of air between said edge and opening.

5. In a whistle having a case forming an air conduit terminating in a constricted air opening and an air deflecting edge aligned with said opening, said case having the configuration of a creature formed thereon, a rigid stem having a lip section formed at one end in the shape of a tongue projecting through the mouth of said creature, means pivotally supporting said stem to permit angular movement of said stem only about a pivotal axis generally parallel to said edge with the lip section adapted to move in a simulated movement of a tongue downwardly to and upwardly from a position between said edge and opening, respectively under the force of gravity and under upward pressure of air against said lip section whereby said lip section will intermittently interrupt the flow of air between said edge and opening.

6. A whistle as set forth in claim 5 wherein said stem has secured thereto an eye disc normally visible through an opening in said casing.

7. A whistle having an air conduit terminating in a constricted air opening, an air deflecting edge aligned with said opening, a resonant chamber with a piston positioned therein for varying the size of said chamber, a rigid stem having a lip section and means pivotally supporting said stem to permit angular movement of said stem only about a pivotal axis generally parallel to said edge with the lip section adapted to move downwardly to and upwardly from a position between said edge and opening, respectively under the force of gravity and under upward pressure of air against said lip section whereby said lip section will intermittently interrupt the flow of air between said edge and opening.

8. A whistle having an air conduit terminating in a constricted air opening, an air deflecting edge aligned with said opening, a resonant chamber with a piston positioned therein for varying the size of said chamber, a rigid stem having a lip section, a piston operating rod secured at one end to said piston and extending out of said resonant chamber at the other end, said rod having projecting elements adapted to actuate an animatable object on movement of said rod, and means pivotally supporting said stem to permit angular movement of said stem only about a pivotal axis generally parallel to said edge with the lip section adapted to move downwardly to and upwardly from a position between said edge and opening, respectively under the force of gravity and under upward pressure of air against said lip section whereby said lip section will intermittently interrupt the flow of air between said edge and opening.

9. A whistle as set forth in claim 8 wherein there is provided said animatable object comprising a creature-like form pivotally secured to said whistle and having a portion engaging said projecting elements whereby said form will pivot on movement of said rod.

10. In a whistle structure, means for simultaneously emitting a warbling whistle of varying frequency and providing animation to an animatable figure and a component portion of it comprising means providing a constricted air flow with an aligned air deflecting edge, a pivotally animated figure, a pivotally supported rigid stem having fixed thereto a lip section and a freely associated component portion of said figure, a resonant chamber with a piston positioned therein for varying the size of said chamber, a piston operating rod secured at one end to said piston and extending out of said resonant chamber at the other end, said rod having projecting elements adapted to pivotally animate said figure on movement of said rod, and means pivotally supporting said stem with the lip section adapted to move to and from a position between said edge and opening whereby said lip section will intermittently interrupt the flow of air between said edge and opening, and said component portion will be simultaneously animated.

11. A whistle as set forth in claim 1, wherein said stem has its upper portion normally visible and formed in the shape of a swing with a bird figure mounted thereon.

12. A whistle as set forth in claim 1, wherein said stem is suspended for pivoting movement by means forming a ball and socket joint.

13. A whistle having an air conduit terminating in a constricted air opening, an air deflecting edge aligned with said opening, a rigid stem pivotally suspended in 10 its center section to permit angular movement of said stem only about a pivotal axis generally parallel to said edge and balanced in a normally vertical position with a lip section extending angularly therefrom, said lip section adapted to move downwardly to and upwardly 15 from a position between said edge and opening, respectively under the force of gravity and under upward pres-

sure of air against said lip section whereby said lip section will intermittently intercept the flow of air between said edge and opening.

14. A whistle as set forth in claim 13 wherein said stem has fixed at its upper end a normally visible figurine adapted to be animated upon movement of said stem.
